CLAIM

The ornamental design for a decanter, as shown and described.

DESCRIPTION

FIG. 1 is a top, front and left side perspective view of a decanter showing my new design;

FIG. 2 is a bottom, rear and right side perspective view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is left side elevational view thereof;

FIG. 8 is a right side elevational view thereof;

FIG. 9 is an exploded isometric view of FIG. 1; and,

FIG. 10 is an enlarged view of the portion labeled "10" framed in FIG. 8.

The broken lines showing the decanter illustrate environmental subject matter and form no part of the claimed design. The remaining broken lines show features of the decanter that form no part of the claimed design. The broken line shown in FIGS. 8 and 10 encircling the enlarged view of FIG. 10 are for annotative purposes only and form no part of the claimed design.

1 Claim, 10 Drawing Sheets
